UNITED STATES PATENT OFFICE.

GEORGE LANE, OF POUGHKEEPSIE, NEW YORK, ASSIGNOR TO LANE BROTHERS COMPANY, OF POUGHKEEPSIE, NEW YORK, A JOINT STOCK ASSOCIATION OF NEW YORK.

DOOR HOLDER.

Application filed September 12, 1923. Serial No. 662,249.

To all whom it may concern:

Be it known that I, GEORGE LANE, a citizen of the United States, and resident of Poughkeepsie, in the county of Dutchess and State of New York, have invented certain new and useful Improvements in Door Holders, of which the following is a specification.

My present invention relates to a door holder for holding open a door of a barn, garage, or other building, and has for its principal object the production of an efficient, durable and convenient holder of low cost and one which presents no manufacturing difficulties; and which will prevent the swinging of the door by the wind, or other cause while a vehicle is entering or leaving the building.

My invention consists essentially of a bar pivoted at one end to the upper part of a door in either a rigid or resilient manner and sliding loosely through a keeper attached to the under side of the door lintel, and means for locking the bar in the keeper.

I have shown a convenient form of apparatus in the drawings, which are to be taken as illustrative only and not in a limiting sense, and in these drawings:

Figure 1 is a plan view of the device as applied to a door and frame, showing the door held open.

Fig. 2 is a side elevation, with the parts in the same position as Fig. 1.

Fig. 3 is an enlarged detail face view of the mounting bracket, with the locking bar in section.

Fig. 4 is a similar view of the keeper for the locking bar.

Fig. 5 is an enlarged sectional elevation of one end of the locking bar and its keeper as attached to the lintel of a doorway, and

Fig. 6 is a detail of a slight modification.

Referring now to the embodiment shown, a door 1 is shown hinged to a wall 2 as of a barn or garage and is adapted to close the opening 3 therein in the usual manner. A plate 4 secured to the upper part of the door as by screws 5 is provided with a projecting stud 6 standing out rigidly from the plate through a slack hole in a bracket 7 for a purpose described hereinafter. Also projecting outwardly in a rigid manner from the plate 4 is a bolt 8 having an enlarged head 9 which retains a coiled spring 10 on the bolt body. Bracket 7 may thus be rocked

on any of its edges to a slight extent, but the stud 6 prevents accidental displacement of the bracket and insures the maintenance of this member in its proper relation to plate 4. The coiled spring 10 insures a return of the bracket to its normal position after any rocking movement.

A bar 11 of channel, L, or crescent cross section is secured to the bracket 7 as by a loose pivot 12, the end of the bar adjacent the pivot preferably terminating as near the pivot as is practical for the purpose of economizing in material and also clearing the door bracket.

The opposite end of the bar 11 passes through a keeper which comprises a main body 13 adapted to be secured to the door lintel 14 and having a depending portion 15 provided with a slot 16 through which the end of the bar 11 is adapted to pass. Near the end of the bar 11 I provide a punched out or struck-up projection 17 on the side of the part 15 farthest from the pivot 12. This projection, while described as a punched out or struck-up portion, may obviously be either integral or a separate element secured to the bar end, the essential point being that the end of the bar be made larger in one dimension than the dimensions of the slot 16 to limit movement of the bar 11 outwardly through the slot.

A notch 20 is provided on the pivot side of the projection 17 and which may be formed in any desired manner. This notch on the upper side of the bar is formed for the purpose of allowing a portion of the member 15 to seat therein, which will prevent relative movement between the bar 11 and the keeper in either direction.

A flat spring 18 is secured to the under side of the bar 11 as by means of rivet 19 and is adapted to bear against the lower edge of the slot 16 in the downwardly projecting portion 15 of the keeper. This causes an upward movement of the keeper end of the bar 11, causing a portion of the part 15 to enter the notch 20, which effectively holds the door in its opened position.

I provide means for causing vertical movement between the bar and the keeper, which may conveniently take the form of a chain 21 attached to the member 11 on the keeper side of the pivot 12 and which may pass through a guide on the door, as shown at 22, and be secured to the door as by screw 110

23. It will now be apparent that a horizontal pull on that portion of the chain between the parts 22 and 23 toward the door opening or in the direction in which the door closes 5 will first cause a depression in the keeper end of the bar 11, thus freeing the keeper from the notch 20, and a further horizontal pull on the chain 21 will cause the door to close.
- 10 It may be found desirable under certain circumstances to mount the bracket 7 rigidly on a plate on the door, such as by providing the right angular portion of the bracket with perforations adapted to receive the screws 24 which securely fasten this member to the door. It will be readily seen, however, that the spring modification is to be preferred, as the spring 10 receives the impact when the door is open to its 15 fullest extent, and the projection 17 engages the portion 15 of the keeper and prevents breakage and undue strain on the parts.
- It has been found that the spring 18 causes a slowing down of the movement of 20 the door in opening when the spring engages the bottom of the slot 16 of the keeper, which serves as a retarding means to prevent a straining of the parts at this end.
- I claim:
- 30 1. A device of the character described, including a keeper secured to a door lintel, a bar sliding in a slot in said keeper, said bar being pivotally carried on a door, and

means having fixed engagement with said bar, and a fixed and sliding engagement 35 with said door and responsive to a horizontal pull for transmitting vertical motion to said bar.

2. A device of the character described, including a keeper secured to a door lintel, a bar sliding in a slot in said keeper, a notch in the top of said bar, and spring means to cause said keeper to enter said notch, a bracket loosely pivoted to said bar, a plate secured to the door having a bolt projecting therefrom and passing through said bracket, and spring means between a head on said bolt and said bracket.

3. A device of the character described, including a keeper attached to a door lintel, 50 a bar sliding in a slot in said keeper, a projection on said bar engaging said keeper, a notch in the top of said bar, spring means secured to the bar, a bearing on the keeper adapted to cause the keeper to be seated in 55 said notch, a bracket loosely pivoted to the opposite end of said bar, and means attached to the pivot end of said bar on the keeper side of the pivot for placing tension on said spring and causing the keeper to 60 ride out of said notch, thereby freeing the bar to slide in the keeper in one direction.

In testimony whereof, I affix my signature.

GEORGE LANE.
